APPARATUS FOR FORMING AND DEWATERING WEBS OF FIBROUS MATERIAL

Willy Stoffel, Nonnenhorn, Wurtemberg, Germany, assignor to Escher Wyss G.m.b.H., Ravensburg, Wurtemberg, Germany, a corporation of Germany

Filed Aug. 27, 1962, Ser. No. 219,582

Claims priority, application Germany, Sept. 8, 1961, E 21,639

4 Claims. (Cl. 162—348)

This invention relates to an apparatus for forming and dewatering webs of fibrous material in the paper industry, or webs of synthetic plastic material, having an endless flexible wire cloth which is guided by means of various rollers from a pulp feeding device over tube rolls and suction boxes to a web-detaching device and back again to the pulp feeding device.

In such apparatus, which are known as Fourdrinier machines, an endless wire cloth made of metal is generally guided about a breast roll arranged at the beginning of the wire part and about a suction roll arranged at the end of the wire part or the lower couch roll of a couch press, whilst the two runs of the wire cloth situated between the aforesaid rolls are stretched out substantially flat. The upper, plane run bears substantially on so-called tube rolls and suction boxes and is effectively guided. The lower run, on the other hand, must be guided by rolls of relatively small diameter which are situated alternately above and below it, the so-called wire guide rolls, which also tension and regulate the wire cloth. The various amounts of deflection occurring as the wire cloth travels about these guide rolls, which cause considerable bending stresses on the longitudinal wires of the cloth, are primarily responsible for rapid wearing of the cloth. In the case of high-speed Fourdrinier machines, the wire cloth must, therefore, be replaced by a new cloth every few days, and this adds correspondingly to running costs and interrupts the otherwise continuous production which is possible.

Wire cylinder machines are also known wherein the wire cloth bears over its entire length on a rigid circular cylindrical supporting drum provided with liquid apertures, there being no relative movement between the wire cloth and the supporting drum. In these wire cylinder machines, the suction boxes must bear on the inner side of the supporting drum. In this way, however, the removal of the water by suction is less effective owing to the resistance to through flow in the holes or apertures provided for the through passage of the liquid in the supporting drum, resulting in accumulations which may have a disadvantageous effect on the formation of the sheet of material. If the suction boxes directly adjoin the wire cloth, such accumulations and therefore their effects are obviated.

The object of the invention is to permit the construction of a machine which does not have the disadvantages of the known Fourdrinier and wire cylinder machines but which combines the advantages of these known machines. In an apparatus of the kind initially specified for forming and dewatering a web of fibrous material, for this purpose according to the invention the suction boxes and the rolls guiding the wire cloth are so arranged and constructed that the wire cloth is disposed substantially in the form of a circular cylinder.

This provides a machine wherein the web of fibrous material is separated from the dewatering chamber, as in the case of the conventional Fourdrinier machine, merely by the thin, permeable wire cloth and wherein nevertheless this wire cloth is subjected in practice to only very slight bending stresses. The result is the best possible dewatering conditions for the web of fibrous

material, and a longer working life for the wire cloth. Furthermore, the machine according to the invention, whilst having a dewatering zone of the same size, manages with a substantially shorter overall length than a Fourdrinier machine, which is a most important feature in view of the size of such machines.

Examples of embodiment of the subject of the present invention are illustrated in a simplified manner in the drawings.

FIGURE 1 is a sectional view through an apparatus at right angles to the axis of the aforesaid circular cylinder.

FIGURE 2 is a sectional view on the line II—II of FIGURE 1 on a larger scale.

FIGURE 3 is a sectional view through a further form of embodiment taken on the line III—III of FIGURE 4, and

FIG. 4 is a sectional view on the line IV—IV of FIGURE 3.

The apparatus shown in FIGURE 1 comprises an endless wire cloth 1 which is guided from a pulp feeding device 3 with adjustable gate 3a, or a plurality of such pulp feeding devices, over rolls 2 with adjustable bars 2a intermediate of the said rolls, and over suction boxes 5 to 8 to a web detaching device 9. By way of a wire cleaning device 10 with spraying nozzles 11 and a trough 12, and by way of driving rolls 13 and 14 with counter-rolls 15 and 16 the wire cloth returns, supported by further rolls 2, to the pulp feed device 3. In the region 30 of the first dewatering zone, the rolls 2 are provided with a save-all 4 having an outflow pipe 4a, or a suction box in accordance with the constructions designated by the reference numerals 5 to 8. The rolls 2 are so mounted and the corresponding surfaces of the suction boxes 5 to 8 are so constructed that the wire cloth 1 is disposed substantially in the form of a circular cylinder and thus guided along a path of substantially circular configuration. In the region of the pulp feed device 3 and in the immediate vicinity thereof, the wire cloth 1 is expediently disposed in a straight fashion for a short distance. Any desired number of the rolls 2 can be constructed as tensioning rolls in which case, as is indicated at one roll, they can be pressed by springs 17 against the wire cloth 1.

The wire cloth 1 is also substantially carried by rolls 2 within the suction boxes 5 and 6, as the detailed view shown in FIGURE 2 illustrates. At the edges, the wire cloth 1 also bears on sealing strips 19 which are arranged in the suction box walls 18, and which, in the example of embodiment, are adapted to be pressed against the wire cloth 1 by a hose 20 into which compressed air can be admitted. Provided between the shaft 21 of the roll 2 and the housing wall 18 is a rubber sealing ring 22. The shaft 21 is mounted by means of ball bearings 23 in a bearing plate 24 fixed to the housing wall 18.

In the apparatus illustrated in FIGURES 3 and 4, the wire cloth 25 departs from the circular cylindrical shape in the region of a driving roll 26, in order to obtain a larger envelope angle for the said driving roll. Also provided are two counter-rolls 27 with which the wire cloth 25 is pressed against the driving roll 26. Over the greater part of its path of travel, the wire cloth 25 follows the outline of a circular cylinder. Only in the driving region is it made to deviate from the circular cylindrical form, but even here only to the extent of the radius of the large driving roll 26.

The wire cloth 1 of FIGURE 1 is subjected to substantially no bending stresses worth mentioning during rotational movement, owing to its guidance along a circular cylindrical path of travel. These satisfactory conditions are obtained for by far the greater part of the path of travel of a wire cloth in the case of the cloth 25 shown in FIGURES 3 and 4.

As FIGURE 4 shows more particularly, in the construction according to FIGURES 3 and 4 the parts situated within the wire cloth 25, namely the suction boxes 29 to 34, the save-all 28, the rolls 35 and the driving roll 26 are mounted in a supporting body fixed in overhung fashion to the base 36 and comprising the parts 37 and 38, and the bearing parts for the suction boxes and rolls are situated inwardly of the cylindrical surface defined by the wire cloth 25. Likewise, the parts situated at the outer side of the wire cloth, namely the rolls 27, the trough 39 for the wire cleaning device and the roll 40 for the web detaching device are mounted on the base 36, and the appropriate bearing parts are situated externally of the cylindrical surface defined by the wire cloth 25.

In order to interchange the wire cloth, all that has to be done, therefore, is to lift some of the rolls 35 away from the wire cloth 25 to retain them in opposition to the action of the springs 41 (FIGURE 4), and the wire cloth 25 can easily be slid in and out through the gap left free between the parts inside and outside the wire cloth (see arrows 42). Insertion can be facilitated by a device which carries the wire cloth to be inserted and which holds it in the aforesaid cylindrical surface.

The rolls 35 can all be constructed to be applied by springs to the wire cloth. The boxes 29 to 34 can also be adapted to be pressed resiliently on the wire cloth, or the rolls can be mounted on fixed axes in a box which can be pressed towards the wire cloth.

The wire drive can also be effected by a relatively larger number of rolls guiding the wire cloth. The driving rolls and also the pairs of rolls 13, 15 and 14, 16 (FIGURE 1) or the rolls 26, 27 (FIGURE 3) can be provided with an elastic covering in order to be careful with the wire cloth.

Furthermore, some of the wire-supporting rolls, as is known in Fourdrinier machines, can be constructed as regulating rolls.

What is claimed is:

1. An apparatus for forming and dewatering webs comprising an endless flexible wire cloth; driving means causing said wire cloth to move in its longitudinal direction; at least one pulp feeding device arranged to supply pulp of fibrous material to the outer surface of said wire cloth so as to form a web thereon; a web detaching device spaced from said pulp feeding device in the longitudinal direction of the wire cloth so as to leave a de-

watering zone between the two; rolls for guiding said wire cloth; and at least one suction box arranged in said dewatering zone; said driving means, guide rolls and suction box being arranged to cause the wire cloth to travel along a path free of reverse bends and of substantially circular configuration at least in the regions of the pulp feeding device, the dewatering zone and the web detaching device.

2. An apparatus for forming and dewatering webs comprising an endless flexible wire cloth, said wire cloth forming a loop; a base; a supporting body connected in overhung fashion to said base; said supporting body comprising wire dewatering means with guiding rolls and at least one suction box arranged internally of said endless wire cloth to support and guide said wire cloth along a path of substantially circular configuration; driving means causing said wire cloth to move in its longitudinal direction; at least one pulp feeding device arranged outside said loop of wire cloth to supply pulp of fibrous material to said wire cloth so as to form a web thereon; and a web detaching device mounted externally of said wire cloth; a gap being left between the parts mounted inside and outside the wire cloth; the gap being left open on one side of the apparatus so as to allow the wire cloth to be removed from the apparatus in a direction transverse to said longitudinal direction.

3. The apparatus defined in claim 1 in which the entire path travelled by the wire cloth is of substantially circular configuration.

4. The apparatus defined in claim 1 in which the path travelled by the wire cloth deviates from the substantially circular configuration in the region of the driving means; and in which the strands of the wire cloth engaging the driving means are tangent to the substantially circular portion of the path.
